UNITED STATES PATENT OFFICE.

CHARLES H. GOODYEAR, OF CEDAR RAPIDS, IOWA.

NOTE-BOOK.

No. 912,112.

Specification of Letters Patent.

Patented Feb. 9, 1909.

Application filed July 16, 1908. Serial No. 443,835.

To all whom it may concern:

Be it known that I, CHARLES H. GOOD-
YEAR, a citizen of the United States, residing
at Cedar Rapids, in the county of Linn and
5 State of Iowa, have invented certain new
and useful Improvements in Note-Books, of
which the following is a specification.

This invention relates to note-books for
the use of stenographers, students, and
10 others, and has for its object to produce a
simple and inexpensive note-book, adapted
to hold the note-paper in a convenient form
for use, and providing for the quick and easy
detachment of the written sheets and the in-
15 sertion of blank sheets to take their places.

The invention is fully disclosed in the
description and claims following, reference
being had to the accompanying drawings,
in which—
20 Figure 1 is a view of the book opened out
flat, as in use. Fig. 2 is a similar view of the
binder, with all the sheets removed. Fig. 3
is a fragmentary view, showing the middle
and upper portion of one of the sheets. Fig.
25 4 is a fragmentary view, showing the upper
part of the binder at the back. Figs. 5, 6
and 7 show details of the hooks to hold the
sheet retaining cords. Fig. 8 illustrates the
manner of attaching a four strand cord to
30 the hooks.

In practice the sheets that form the con-
tents of the note-book are perforated and
notched as shown in Figs. 1 and 3. It will
35 be seen that the sheet A is notched at B, both
top and bottom, and is perforated at C along
the middle of the sheet. The holes at D are
for filing on the studs of a transfer binder,
not shown. A number of these sheets,
40 usually about six, forms a section, folded
along the line of perforations.

The binder is composed of a pair of stiff
covers E, preferably hinged to a stiff back-
strip F. Attached to the back at the top
45 and bottom is a hook G, which as shown
herein is threefold and formed with an eyelet
H, which for neatness is clenched through a
washer I at the back, as shown in Fig. 4.
About the prongs of this hook is looped the
50 section retaining cord J, preferably elastic,
and connected by a suitable end fastener at

K. The course of the cord is shown in Fig.
8, where it will be evident that the two bot-
tom loops pass around the two outer prongs
of the hook, the outer loop at the top passes
over all three prongs, and the inner top loop 55
over the middle prong. The construction is
such as to admit of the cord being very
quickly attached to the binder back in the
process of manufacture, and when in position
the various strands are parallel and do not 60
cross at any point. The various sections
are slipped under these separate strands, the
notches at the top and bottom serving to
keep them very accurately in position.

For convenience in clenching the eyelets 65
of the hooks, the latter are originally formed
flat, and being of lighter brass are easily bent
to hook form by the fingers. The number of
prongs may vary according to the number of
sections used, a single hook at each end serv- 70
ing for a pair of sections, while a five-pronged
hook would take six strands and sections,
and so on.

The user of the note-book is supposed to
fill both opposite pages of the sheet, or more, 75
and then detach the sheet by tearing it along
the cord through the central line of perfora-
tions.

Having thus described my invention, I 80
claim.

1. A note-book binder, comprising a pair
of covers and a back, a multiple pronged
hook attached by an eyelet to the inside of
the back near the top and bottom, and a 85
continuous cord looped about said hooks,
and lying in parallel and uncrossing strands.

2. A note-book, substantially as described,
comprising one or more sections of folded
and centrally perforate leaves having cord-
engaging notches at the top and bottom, 90
and a retaining binder, comprising a pair of
covers and a back, a hook attached to the
inside of the back near the top and bottom,
and an elastic cord looped about said hooks.

In testimony whereof I affix my signature 95
in presence of two witnesses.

CHARLES H. GOODYEAR.
